(57) **CLAIM**

The ornamental design for a drinking glass, as shown and described.

DESCRIPTION

FIG. 1 is a front elevation view of a drinking glass showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a cross-sectional view showing a section taken along line 7-7 in FIG. 1 thereof;

FIG. 8 is a top, right, front perspective view thereof; and,

FIG. 9 is a top, right, front perspective view thereof in an in-use configuration.

The broken lines in the drawings depict portions of the drinking glass that form no part of the claimed design.

The shaded portions of FIG. 9 illustrate environmental structure and form no part of the claimed design.

1 Claim, 9 Drawing Sheets
